UNITED STATES PATENT OFFICE.

CHARLES A. ALDEN, OF STEELTON, PENNSYLVANIA.

TOBACCO PIPE.

Application filed March 23, 1925. Serial No. 17,514.

To all whom it may concern:

Be it known that I, CHARLES A. ALDEN, a citizen of the United States, residing at Steelton, in the county of Dauphin and State 5 of Pennsylvania, have invented certain new and useful Improvements in Tobacco Pipes, of which the following is a specification.

This invention relates to improvements in that class of tobacco pipes wherein the pipe 10 stem extends from the upper portion of the pipe bowl and wherein parts of the pipe are separable from one another for cleaning purposes.

The object of my invention is to provide 15 a pipe having parts of novel construction which may be manufactured at low cost and which are so constructed and related to each other as to provide a smoke passage between the tobacco receptacle of the bowl and the 20 mouth piece of the stem which may be easily and quickly cleaned and which will effectually prevent the semi-liquid and other objectionable matter which finds its way into the various parts of the passage, as a result 25 of the smoking operation, from reaching the mouth piece and being discharged therefrom, while the pipe is being smoked, and from being returned to the tobacco receptacle when the pipe is turned or inverted.

With the foregoing and related objects in view, the invention consists of the elements 30 and the combinations of them hereinafter described.

In the accompanying drawings, illustrating 35 my invention,

Figure 1 is a top view of my improved pipe.

Figure 2 is a longitudinal section of the pipe, on line 2—2 of Fig. 1.

Figure 3 is a horizontal section through the pipe bowl, on line 3—3 of Fig. 2.

Figure 4 is a top view of the detachable base member of the bowl.

Referring to the drawings, 4 designates 45 the pipe bowl having the hollow portion 5 which forms a receptacle for tobacco to be smoked therein.

The bowl 4 is provided with a stem 6 which extends outwardly from the upper 50 portion thereof. The stem 6 has an axial opening or socket 7 extending inwardly from the outer end thereof for the reception of the reduced end portion 8 of a mouth piece 9 which forms, in effect, a continuation 55 of the stem 6. The mouth piece 9 may be detached from the stem by withdrawing

the reduced end portion 8 thereof from the opening 7; and, when the end portion 8 is inserted into the opening 7, the frictional engagement of the parts holds the stem and 60 mouth piece together.

The bottom portion of the bowl 4 is made hollow and the hollow portion is interiorly screw-threaded, as shown in the drawings. 65 The hollow bottom portion of the bowl carries a base member 10 which is exteriorly screw-threaded and screwed into the same and the bottom of which is provided with an outwardly-projecting, annular flange 11 adapted to engage the bottom surface of the 70 bowl 4 and limit the movement of the base member 10 when it is screwed into the bowl. The flange 11 also serves as a hand grip for the base member 10 when it is unscrewed to 75 remove it from the bowl.

The base member 10 is so related to the bowl 4 that when it is screwed into the same a space is provided between the top of the member 10 and the bottom wall 12 of the 80 bowl 4 forming a chamber 13 between them. The central portion of the top wall 12 of the chamber 13 has an upwardly extending hollow or cavity 14 formed therein, and the central portion of the top of the base member 10 or bottom wall of the chamber 13 has 85 a downwardly extending hollow or cavity 15 formed therein beneath the cavity 14, as clearly shown in Fig. 2, for purposes herein-after described.

The mouth piece 9 and stem 6 have central 90 smoke passages 16 and 17, respectively, therein, forming continuations of one another; the bowl 4 has a smoke passage 18 therein which communicates at its lower end with the chamber 13 and at its upper end 95 with the passage 17 in the stem 6; and the wall 12 of the bowl 4, forming the bottom of the tobacco receptacle 5, has passages or ports 19 therein which connect the hollow portion or receptacle 5 and the chamber 13. 100

It will now be understood that the ports 19, chamber 13 and passages 18, 17 and 16 form, in effect, one continuous passage from the tobacco receptacle 5 to and through the mouth piece 9, through which smoke may 105 be drawn by the person using the pipe.

The upper portion of the bowl 4, at or near its junction with the stem 6, has an opening 20 therein above the upper end of the passage 18 and communicating with the 110 passages 17 and 18. This opening 20 is normally closed by a screw-threaded plug

21 which is screwed into the opening 20 and which is provided with a suitable head 22 by means of which the plug may be handled. The head 22 also serves to engage the top 5 of the bowl and limit the movement of the plug when it is screwed into place.

When the plug 21 and base member 10 are removed from the bowl 4, the opening 20 in the bowl 4 together with the smoke 10 passage 18 therein provides a straight and unobstructed opening of the full diameter of the passage 18 from the space beneath the bowl to the space above the same. This construction not only permits the passage 18 to 15 be easily drilled or otherwise formed by a suitable instrument in making the pipe, but it also permits a cleaning device to be passed through the passage in a straight line when it is desired to clean the same. The opening 20 20 also serves to permit an entire cleaning device to be passed completely through it and the smoke passage 17 when the mouth piece 9 and plug 21 are removed and it is desired to clean the passage 17.

25 The cavity 15 in the base member 10 provides a settling basin for the accumulation therein of the semi-liquid and other objectionable matter, well known to smokers, which finds its way into the chamber 13 and 30 the other smoke passages of the pipe. After the base member 10 has been removed from the bowl 4, this objectionable matter may be readily cleaned from the cavities 14 and 15 and other parts of the chamber 13.

35 The arrangement of the cavity 15 directly beneath the cavity 14, and the arrangement of the passage 18 and ports 19 outwardly or laterally of the cavity 14, causes the accumulated matter within the cavity 15 to be 40 discharged into the cavity 14 and prevents it from entering the passage 18 and ports 19 when the pipe is inverted, and causes the said matter to be returned to the cavity 15 when the pipe is turned right side up after 45 being inverted.

It will be observed that the screw threads 50 of the base member 10 surround the cavity 15 therein outwardly thereof. This construction separates the threads from the cavity and thereby prevents the accumulated matter within the cavity from reaching the threads by gravity when the member 10 is removed for cleaning purposes, thereby 55 keeping the threads clean and ready for replacement after the fouled parts of the pipe have been cleaned.

I claim as my invention:—

60 1. A tobacco pipe comprising a bowl forming a tobacco receptacle, a stem extending from the upper portion of the bowl and having a smoke passage therein, a base member detachably connected to the lower portion of the bowl, the bowl and the base member forming a chamber between them 65 for receiving matter resulting from smoking

the pipe, and the bowl having a port therein connecting said receptacle and said chamber and having a smoke passage therein communicating at its lower end with said chamber and at its upper end with the passage in 70 the stem, and a removable plug contained within an opening in the upper portion of the bowl, said opening communicating with said passages and affording access thereto when the plug is removed. 75

2. A tobacco pipe comprising a bowl forming a tobacco receptacle, a stem extending from the upper portion of the bowl and having a smoke passage therein, a base member detachably connected to the lower portion of the bowl, the bowl and the base member forming a chamber between them for receiving matter resulting from smoking the pipe, and the bowl having a port therein connecting said receptacle and said chamber and having a smoke passage therein communicating at its lower end with said chamber and at its upper end with the passage in the stem, and a removable plug contained within an opening in the upper portion of the bowl, said opening and the passage in the bowl providing a straight opening of the full diameter of the passage from 80 the space beneath the bowl to the space above the same. 85

3. A tobacco pipe comprising a bowl forming a tobacco receptacle, a stem extending from the upper portion of the bowl and having a smoke passage therein, and a base member detachably connected to the lower portion of the bowl, the bowl and the base member forming a chamber between them for receiving matter resulting from smoking the pipe, the bottom part of the bowl forming the top wall of the chamber 90 having an upwardly extending cavity therein, and the bowl having a port therein laterally of the cavity connecting said receptacle and said chamber and having a smoke passage therein laterally of the cavity and communicating at its lower end with the said chamber and at its upper end with the passage in the stem. 95

4. A tobacco pipe comprising a bowl forming a tobacco receptacle, a stem extending from the upper portion of the bowl and having a smoke passage therein, and a base member detachably connected to the lower portion of the bowl, the bowl and the base member forming a chamber between them for receiving matter resulting from smoking the pipe, the bottom part of the bowl forming the top wall of the chamber 100 having an upwardly extending cavity therein, the top part of the base member forming the bottom wall of the chamber having a downwardly extending cavity therein beneath the first named cavity, and the bowl 105 having a port therein laterally of the cavity therein connecting said receptacle and said 110

chamber and having a smoke passage therein laterally of the cavity therein and communicating at its lower end with said chamber and at its upper end with the passage in 5 the stem.

5. A tobacco pipe comprising a bowl forming a tobacco receptacle, a stem extending from the upper portion of the bowl and having a smoke passage therein, and 10 a base member detachably connected to the lower portion of the bowl, the bowl and the base member forming a chamber between them for receiving matter resulting from smoking the pipe, the bottom part of the 15 bowl forming the top wall of the chamber having a central, upwardly extending cavity

therein, the top part of the base member forming the bottom wall of the chamber having a central, downwardly extending cavity therein below and spaced from the 20 first named cavity, said chamber having an outwardly extending portion surrounding the space between said cavities, and the bowl having a port therein connecting the outwardly extending portion of the chamber 25 and the receptacle and having a smoke passage therein connecting the outwardly extending portion of the chamber and the passage in the stem.

In testimony whereof I affix my signature 30 hereto.

CHARLES A. ALDEN.
